Percy Freeman

ATTORNEY.

UNITED STATES PATENT OFFICE

2,482,871

PAPER ROLL HOLDER

Solomon Rapport, New York, N. Y.

Application August 21, 1945, Serial No. 611,731

4 Claims. (Cl. 242—55.2)

1

This invention relates generally to toilet paper roll supports, and particularly to brackets adapted to be attached to a wall or other supporting surface, and provided with resilient means engaging within the core opening in the paper roll to support the roll and to permit unwinding of the roll as paper is taken therefrom.

An object of this invention is to provide a bracket or support of the character described having resilient arms engaging the inner surface of the through opening in the paper roll to yieldingly and frictionally contact the same for permitting unwinding of the roll.

Another object of this invention is to provide a strong, rugged and durable bracket of the character described which shall be relatively inexpensive to manufacture, easy to assemble, and which shall yet be practical and efficient to a high degree in use.

Other objects of this invention will in part be obvious and in part hereinafter pointed out.

The invention accordingly consists in the features of construction, combination of elements, and arrangement of parts which will be exemplified in the construction hereinafter described, and of which the scope of application will be indicated in the following claims.

In the accompanying drawing, in which is shown various possible illustrative embodiments of this invention:

Fig. 1 is a side elevational view of a bracket embodying the invention.

Fig. 2 is a top plan view thereof.

Fig. 3 is an end view thereof.

Fig. 4 is a view similar to Fig. 1 but illustrating a modified construction.

Fig. 5 is a top view of the structure shown in Fig. 4.

Fig. 6 is an end view of the structure shown in Fig. 4.

Fig. 7 is a partial cross-sectional view taken on line 7—7 of Fig. 1.

Referring now in detail to the drawing, 10 designates a bracket embodying the invention, to support a toilet roll designated by numeral 11. The bracket 10 comprises a member 12 made of sheet metal, the same comprising a base 13, formed with a pair of spaced through openings 14 to receive screws, nails or other fastening means for attaching the bracket to a wall or other support.

Extending from base 13 at right angles thereto is an arm 16, offset as at 17, and continuing in the same direction to provide an extension 18 parallel to arm 16. Extension 18 is formed with

2

a through opening 20 for the purpose hereinafter appearing. Attached to extension 18 in the manner hereinafter described is a U-shaped spring member 25 which comprises a central, transverse wall 26 contacting the inner surface of extension 18. Wall 26 is formed with a central opening 27 registering with opening 20. Extending from wall 26, substantially at right angles thereto, are a pair of similar, symmetrically disposed spring arms 29 having inwardly curved end fingers 30. Arms 29 may diverge slightly away from wall 26 as shown in Fig. 3 of the drawing.

There is also attached to extension 18 in the manner hereinafter appearing, a member 33 comprising an intermediate portion 34 from which there extends a pair of spring arms 35. Wall 34 crosses wall 26 at right angles thereto and is formed with an intermediate recessed portion 36 straddling wall 26. The portions of wall 34 on opposite sides of the recessed wall 36 contact the inside of extension 18. The recessed wall 36 is formed with a central opening 38 which registers with openings 27 and 20, and extending through these registering openings is a rivet 40 having a head 41 at the top. A washer 42 may be interposed between the inner end of rivet 40 and the recessed portion 36. The U-shaped members are rotatably connected to extension 18 by the rivet. The connection is such, however, that said U-shaped members do not wobble.

Arms 35 likewise diverge as shown in Fig. 2 of the drawing. At the outer ends of arms 35 are inwardly curved fingers 35a.

It will now be understood that the spring arms 29, 35 enter the opening at one end of the toilet paper roll 11 and resiliently press against the inner surface of said opening. As the toilet paper roll unwinds, the U-shaped members rotate together with the roll.

In Figs. 4, 5 and 6, there is shown a bracket 10a embodying the invention and illustrating a modified construction thereof. The bracket 10a comprises a wall plate 50 having a central wall portion 51 from the ends of which extend short parallel offset shoulder portions 52. Extending outwardly from walls 52 are aligned base portions 53 parallel to wall 51. Base portions 53 are each formed with an opening 54 to receive a screw, nail or like fastening means for fastening the bracket 10a to a support. Attached to wall 51 are members 25 and 33, the same as in bracket 10. Said members 25 and 33 are rotatably attached to member 50 by means of a rivet 40, in the same manner as for bracket 10.

It will thus be seen that there is provided a

device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, what I claim as new and desire to secure by Letters Patent is:

1. A bracket for supporting a toilet paper roll, comprising a member formed with openings to receive fastening means for attachment to a support, a pair of U-shaped members, each comprising an intermediate portion, and a pair of spring arms, said U-shaped members being rotatably attached to the first member with the intermediate portions contacting said first member crossing one another, the spring arms of each U-shaped member diverging away from the intermediate portion and having inwardly curved fingers at the outer ends thereof.

2. A bracket for supporting a toilet paper roll, comprising a member formed with openings to receive fastening means for attachment to a support, a pair of U-shaped members, each comprising an intermediate portion, and a pair of spring arms, said U-shaped members being rotatably attached to the first member with the intermediate portions contacting said first member crossing one another, the spring arms of each U-shaped member diverging away from the intermediate portion and having inwardly curved fingers at the outer ends thereof, one intermediate portion having a recessed portion straddling the other intermediate portion.

3. A bracket for supporting a toilet paper roll, comprising a member formed with openings to receive fastening means for attachment to a support, a pair of U-shaped members, each comprising an intermediate portion, and a pair of spring arms, said U-shaped members being rotatably attached to the first member with the intermediate portions contacting said first member crossing one another, the spring arms of each U-shaped member diverging away from the intermediate portion and having inwardly curved fingers at the outer ends thereof.

outer ends thereof, one intermediate portion having a recessed portion straddling the other intermediate portion whereby both said portions are interlocked to prevent relative rotation between them, the attachment of said U-shaped members to said first member being by means of a rivet passing through registering openings in the first member and in said intermediate portions.

4. A toilet paper roll bracket comprising a member having a base, an arm extending at right angles to the base and formed with an offset, and an extension on said offset parallel to the said arm, said base being formed with openings to receive attaching devices for attaching said member to a support, said extension being formed with a through opening, a U-shaped member comprising an intermediate portion contacting said extension, and a pair of spring arms extending from said intermediate portion, said intermediate portion being formed with an opening registering with the opening in said extension, a second U-shaped member in a plane at right angles to the first U-shaped member and comprising an intermediate portion contacting said extension and having a portion straddling the first intermediate portion whereby said intermediate portions are interlocked to prevent relative rotation between them, a pair of spring arms extending from said second intermediate portion, said second intermediate portion being formed with an opening registering with the openings in the first intermediate portion and in said extension, and a rivet extending through said registering openings to rotatably fasten said U-shaped members to said extension, the spring arms of each U-shaped member diverging away from the intermediate portions and having inwardly curved fingers at the outer ends thereof.
